UNITED STATES PATENT OFFICE.

IRVING R. SMITH, OF WAUWATOSA, WISCONSIN.

TRUCK.

Application filed June 13, 1921. Serial No. 477,034.

To all whom it may concern:

Be it known that I, IRVING R. SMITH, a citizen of the United States, residing at Wauwatosa, in the county of Milwaukee and

5 State of Wisconsin, have invented certain new and useful Improvements in Trucks, of which the following is a specification.

The present invention relates to trucks.

More particularly the present invention 10 relates to trucks of the variety commonly referred to as hand trucks although the invention is also applicable to other varieties of truck.

An object of the present invention is to 15 provide a truck which may be readily assembled and disassembled and which provides a sturdy structure at a minimum cost.

A further object is to provide a structure 20 which may be shipped in knock-down condition and which may be assembled with the exercise of only a minimum amount of discretion on the part of a workman.

Other objects will appear as the description proceeds.

25 Referring to the drawings, Figure 1 represents in plan view a truck embodying the present invention.

Figure 2 is a sectional view in elevation, taken along the line 2—2 of Figure 1.

30 Figures 3 and 4 show details of construction, taken along the lines 3—3 and 4—4 respectively of Figure 1.

Broadly stated, the present invention contemplates the use of side pieces which may be 35 of wood or other material, said side pieces being joined rigidly together at their end portions to form a rigid frame. The improvements contained in the present invention relate to the means for joining said side 40 pieces together as well as to the complete structure.

The side pieces of the truck are indicated by the numerals 1—1. The side pieces 1—1 are shown located to form a rectangular frame, the corners between adjacent side 45 pieces being provided with clamping members which will be described hereinafter.

The clamping members at the left hand end of the truck, as shown in Figure 1, are 50 indicated by the numerals 2—2, while the clamping members at the right hand end of the truck are indicated by the numerals 3—3. The clamping members 2—2 each comprise a pair of jaw members 4 and 5. Each jaw 55 member 4 fits within a corner between adjacent side pieces 1—1 while a jaw member

5 fits outside of said corner. Each jaw member 4 has a pair of jaws indicated by the numerals 6—6, while each jaw member 5 has a pair of jaws 7—7. Each jaw 6 lies in parallel relation with the cooperating jaw 7 and is adapted to tightly grip the end portion of a side piece 1. Bolts 8—8 are provided for drawing the jaw members 4 and 5 toward jaw closing position whereby said jaw members will tightly grip and unite adjacent side pieces 1—1. As will be clear from the drawing, each bolt 8 is angularly placed relative to the adjacent side pieces 1—1, said bolt extending in a direction having substantially equal angularity with reference to the two adjacent side pieces. Each of the jaw members 5—5 is provided with a socket portion 9 for the reception of an upright or standard 9', which may serve as a handle. 70 In the claims forming part of this specification the socket portions 9—9 are referred to as handle members.

Referring now to the clamping means at the right hand end of the truck as shown in Figure 1, each of said clamping means comprises a pair of jaw members 10 and 11. Each jaw member 11 is provided with a pair of jaws 6—6, while each jaw member 10 is provided with jaws 7—7 which may be similar in construction to the jaws of the clamping members previously described. Each jaw member 10 is provided with a socket member 9 serving the same purpose as the corresponding structure in the jaw members at the left hand end of the truck. Bolts 8—8 serve to draw together the jaw members 10 and 11 to tightly grip the end portions of the side members to hold same rigidly together. The jaw members 11—11 may each be provided with a socket member 12 for the reception of the stud 13 of a caster 14. The roller member of said caster 14 is indicated by the numeral 15.

Oppositely placed side members 1—1 may 100 be provided on their under sides with brackets 16 for the reception of an axle 17. Said axle 17 will carry a pair of spaced wheels 18—18 which with casters 15—15 will form the rolling members for the truck. 105

It will be understood of course that jaw members 11—11 which are provided with caster receiving sockets may be used at all of the corners of the truck if preferred, in which case the wheels 18—18 with their supporting members will be dispensed with.

The preferred embodiment of the present

invention has been described in detail. Many modifications will occur to those skilled in the art. It is intended in this patent to cover all such modifications that fall within the scope of the invention as defined by the appended claims.

What I claim as new and desire to secure by Letters Patent in the United States, is:

1. In combination, a plurality of side pieces, located to form a substantially closed frame and clamping means for rigidly holding together adjacent end portions of said side pieces, each of said clamping means comprising a pair of clamping pieces provided with jaws for holding the end portions of adjacent side pieces, the angle between the jaws of each clamping piece being the same as the angle between the jaws of its co-operating clamping piece and parallel bolt means for drawing said clamping pieces toward jaw closing position, each of said clamping means being provided with a handle member.
2. A truck comprising side pieces located to form a substantially closed frame, clamping means for securing together end portions of adjacent side pieces, each of said clamping means comprising a pair of jaw members adapted to fit inside and outside of the corner between adjacent side pieces and means for drawing said jaw members toward closing position, each of said clamping means being provided with a handle member and certain of said clamping means being provided with caster receiving sockets.
3. A truck comprising side pieces located to form a substantially closed frame, clamping means for securing together end portions of adjacent side pieces, each of said clamping means comprising a pair of jaw members adapted to fit inside and outside

of the corner between adjacent side pieces and means for drawing said jaw members toward closing position, certain of said clamping means being provided with caster 45 receiving sockets.

4. A truck, comprising side pieces located to form a substantially closed frame, clamping means for securing together end portions of adjacent side pieces, each of said clamping means comprising a pair of jaw members adapted to fit inside and outside of the corner between adjacent side pieces, and means for drawing said jaw members toward closing position, each of said jaw members comprising a pair of angularly placed jaws, the angle between the jaws of one of said jaw members being the same as the angle between the jaws of its co-operating jaw member, said drawing means comprising a plurality of parallel bolt means.

5. In combination, a plurality of side pieces located to form a substantially closed frame and clamping means for rigidly holding together adjacent end portions of said side pieces, each of said clamping means comprising a pair of clamping pieces provided with jaws for holding the end portions of adjacent side pieces, the angle between the jaws of each clamping piece being the same as the angle between the jaws of its co-operating clamping piece and bolt means for drawing the clamping pieces of each of said clamping means toward jaw closing position, each of said clamping means being provided with a handle member, said bolt means extending in a direction having substantially the same angularity of each of the two adjacent side pieces.

Signed at Chicago, Illinois, this 9th day 80 of June, 1921.

IRVING R. SMITH.
